SHINGLE

Norman P. Harshberger, Scarsdale, N. Y., assignor to Bakelite Building Products Co., Inc., New York, N. Y., a corporation of Delaware

Application December 21, 1931, Serial No. 582,377

13 Claims. (Cl. 108—8)

This invention relates to improvements in shingles and method of producing the same.

Rigid shingles for roofing and siding purposes have, in recent years, been received with considerable favor due to the fact that they are more fire-proof, more massive in appearance, and more durable than the usual form of flexible composition covering. These shingles are commonly manufactured from a mixture of cement and asbestos fibers formed by a suitable method, such as by molding, to a desired shape, and then subjected to high pressure. Due to the fact that each shingle must be put individually through the various steps in the manufacturing process, the cost of the article is relatively high so that the field of use has been necessarily limited.

It is one of the objects of this invention to provide an improved method of producing rigid shingles which entails the minimum of manufacturing expense and which, nevertheless, forms a very effective and durable product.

A more specific object of this invention is to provide a method of producing shingles which makes it possible to form and cut a plurality of rigid elements, of any conventional shape, from a traveling web to thereby increase production and eliminate the usual expense of forming each element separately.

A further specific object of the invention is to provide a method which includes the coating of a continuous web of inexpensive, relatively thin flexible material, such as paper, with hydraulic cement or the like, and the cutting of said coated web to form a plurality of individual elements therefrom before the cement has completely set, the paper acting as a vehicle to hold the cement in web form prior to hardening of said cement.

A further object of the invention is to provide a method of producing shingles which includes the coating of a continuous web of relatively thin flexible material on both sides with hydraulic cement and the cutting of the web in such a manner as to form a plurality of elements of desired shape having their cut edges protected by the coating.

A further object of this invention is to provide as a new article of manufacture a shingle consisting of a relatively thin core of paper or the like covered with hydraulic cement. The product is to be distinguished from products wherein a relatively thick core, such as wood, is coated with cement, as in such a product the core forms a major portion of the finished product. In the present form of shingle, however, the paper forms a minor part of the final product, the cement

forming the major portion thereof. In the final product the paper is not conducive to cracking of the cement coating since it forms only a minor part of the total bulk, and is not adapted to control the movements of the cement portion which are occasioned by moisture, thermal expansion or contraction, or to contraction brought about by curing and ageing. In this respect it is a considerable improvement over cement shingles having a metal or wood core and should also be distinguished from the standard weight felt shingles having a cement coating on one side thereof as here the felt forms a considerable portion of the total product and provides different characteristics. Moreover, paper has considerably greater strength for its thickness than other materials which could be used as a core and therefore has the ability of holding the product together in the event of fracture due to long use and handling.

With the above and other objects in view, the invention consists of the improved shingle and method of producing the same, and all its parts and combinations as set forth in the claims, and all equivalents thereof.

In the drawing, Figure 1 is a side elevational view partially diagrammatic, showing the method of forming the web to produce the improved shingle;

Fig. 2 is an enlarged sectional view taken transversely through the web, showing complementary cutting knives acting thereon while the coating is in a semiplastic condition;

Fig. 3 is a similar view wherein an upper cutting knife only is utilized, the web being supported by a roll below;

Fig. 4 is a plan view showing one form of cutting which may be produced, part being broken away;

Fig. 5 is a sectional view taken on line 5—5 of Fig. 4;

Fig. 6 is a view similar to Fig. 5 showing a modified form of element wherein there is a double coating;

Fig. 7 is a plan view showing another type of element having a perforated core, part being broken away;

Fig. 8 is an enlarged sectional view taken on line 8—8 of Fig. 7;

Fig. 9 is a plan view showing still another type of element wherein the core is embossed or roughened, part being broken away; and

Fig. 10 is an enlarged sectional view taken on line 10—10 of Fig. 9.

In forming the improved product, any form

of paper or thin flexible material may be utilized, the only requirement being that the paper has sufficient strength to carry the weight of the cement to be applied thereto. Any inexpensive 5 commercial form of paper is satisfactory, but if desired, a more expensive form may be utilized such as a two-ply paper with an intervening layer of strengthening fibers or the like.

The paper, designated by the numeral 12, which 10 may or may not be treated with asphalt or other water-proofing material, is led over a guiding roller 13 as shown in Fig. 1, and is then subjected to a coating process. Any suitable means may be utilized for applying the coating thereto. It is 15 preferred, however, to cause the paper, while traveling, to be submerged in a tank 14, the said tank having hydraulic cement 15 therein. The ordinary form of Portland cement may be utilized or a suitable oxysalt cement with a proper liquid 20 binder. An oxychloride cement is very satisfactory. This type of cement is preferable for the second coating, where two coatings are used as shown in Fig. 6, because it is more dense than Portland cement, and because it forms a smoother, 25 more finished surface. As the traveling web emerges from the tank, there will be a relatively thick coating on both sides of the paper. Any suitable means such as the roll 16 may be employed for leveling the coating and for gauging 30 it to a desired thickness. The web may then be passed over a suitable movable support, as the endless belt 17, and below a cutting roll 18, having knives 19 thereon, as shown in Figs. 2 or 3.

These knives engage the web before the cement 35 has set, and in severing the web to form shingles of a desired shape, they tend to compress the soft cement at the severed edges, as shown in Figs. 2 and 3, and to cause it to curve around the edges of the paper core, so that the paper at all 40 of the severed edges is thoroughly protected. In addition, the pressure of the cutting knives tends to compress the edges of the paper, as at 20, to render the latter more dense at the cut edges and thereby prevent the entrance of moisture to the 45 paper.

The cement utilized in the tank 14 may be mixed with color therein so as to form shingles of any desired shade. As an alternative, the color 50 may be applied to the surface of the cement after the latter has been coated on the paper.

If desired, the paper may be treated, prior to 55 its entrance into the coating tank 14, with a suitable adhesive, such as emulsified asphalt or any other bituminous material, casein, glue or the like, to aid in binding the cement to the paper, while the cement is in the process of setting. An emulsified asphalt is preferable because the liquid in emulsified asphalt, before it has set, will combine with liquid in the cement to bond the 60 two together. A better bond is also obtained since there is not the tendency of the wet cement to set the emulsified asphalt by chilling, as would occur with ordinary molten asphalt.

With the above method, it will be seen that 65 the paper serves effectively as a vehicle for carrying the cement in web form to permit a continuous coating operation, and that the paper forms a minor part of the bulk of the completed product, the thickness of the cement in the final 70 product being several times that of the paper. By means of this method, any of the conventional forms of roofing may be readily formed from cement, and many of these forms are far superior when formed from cement than when 75 made of the usual flexible composition material.

When the latter is used, shingles of the shape shown in Fig. 4, having a relatively narrow neck 21, are objectionable, as the usual asphalt coating has insufficient strength to prevent breakage of said neck. By forming shingles of 5 cement, however, the latter will strengthen the narrow portions of the body brought about by spaced openings between tabs, and the result will be a very durable product.

In order to make a still more substantial 10 shingle, a second coating of cement, preferably an oxysalt, as indicated at 22 in Fig. 6 may be applied, preferably after the first coating has partially set, and either before or after the web has been cut.

It is preferred to use in the cement mixture contained in the tank 14, asbestos fibers or the like, which will tend to hold the cement together 15 after it has set.

In Fig. 7 is illustrated another form of shingle 20 which may be made with the improved process. In this form a slight modification is illustrated wherein the paper core is provided with a plurality of perforations 23. The cement covering will naturally flow through said perforations, and 25 thus the cement will be firmly anchored in place.

In Fig. 9 still another shape of shingle is shown wherein the paper has an embossed or roughened surface as at 24, the said embossed areas furnishing projections to which the cement will become 30 firmly anchored after it has set.

While it is preferred to utilize the coating on both sides of the paper, it may, of course, be applied to one side thereof only, and the coating on one or both sides may be omitted from portions 35 which are adapted to be covered over during assembly.

From the above, it may readily be seen that a rigid shingle has been provided which can be formed in an economical manner from a web and 40 cut into any conventional shape, and it may be seen that the filler utilized is relatively inexpensive and forms but a small portion of the thickness of the finished product.

Thus the cement will be the major portion of 45 the product, and it will therefore be the controlling factor in expansion and contraction. In view of the fact that the base has a different coefficient of expansion and contraction than cement, if the base forms a major part of the 50 thickness such as would be the case if ordinary base material were employed, the difference in coefficients of the base and the cement would be likely to cause cracking of the cement when the product is subjected to temperature changes. 55 Likewise if the base, for instance, metal, is such that it cannot be controlled by movements of the cement, occasioned by moisture absorption or shrinkage due to curing and ageing, cracking also will likely occur. Furthermore, by the use of 60 paper instead of felt, the filler will have considerably greater strength and density in proportion to its thickness.

An advantage in the use of hydraulic cement as a coating lies in the fact that the water of 65 the cement serves to keep the cutting knives dampened to afford desired lubrication. When an oleaginous material is used as a coating, the knives must be lubricated by spraying or by the application of water from a container, and with 70 this method, an undesirable excess of water on the knives usually results.

The formation of the product in web form is, of course, the most economical, as it permits rapid production. Individual shingles can, how- 75

ever, be produced by cutting paper to desired shapes, and by dipping the whole or portions of the paper into hydraulic cement, the latter completely covering the surfaces and edges of the 5 dipped portion.

While only a few forms of the invention have been shown and described, it is to be understood that all changes and modifications are contemplated as may come within the scope of the 10 claims.

What I claim is:

1. As a new article of manufacture, a shingle for exposure to the weather comprising a relatively thin paper membrane having a coating of 15 hydraulic cement thereon wholly enclosing the membrane at all the edges thereof.

2. As a new article of manufacture, a shingle for exposure to the weather comprising a relatively thin paper membrane having a coating 20 on both sides thereof, said coating extending substantially to all edges of the membrane and extending over all edge portions to be exposed to the weather when laid.

3. As an article of manufacture, a hydraulic 25 cement shingle element for weather exposure comprising a main portion of cementitious material and a forming core comprising a thin paper membrane, said cementitious material wholly enclosing the membrane.

30 4. As an article of manufacture a shingle comprising a paper core and a coating of hydraulic cement thereon, said coating surrounding said core and being compressed at the edge portions thereof.

35 5. As an article of manufacture, a hydraulic cement shingle comprising a body, the major bulk of which is cementitious material and a thin fibrous core, said core being compressed at the 40 edge portions, whereby moisture is sealed out.

6. As an article of manufacture, a cementitious shingle element comprising a relatively thin fibrous layer and a hardened hydraulic cement coating secured thereto, said coating being of greater density at the edge portion of the shingle 5 than at the area within said edges.

7. As an article of manufacture, a shingle element comprising a base, consisting of a fibrous membrane, a layer of Portland cement on said base and a layer of oxychloride cement upon said 10 first layer to form a surfacing therefor.

8. A shingle element comprising a layer of hydraulic cement and a surfacing thereon comprising an oxychloride cement.

9. As an article of manufacture, a shingle 15 element comprising a paper membrane and a hardened hydraulic cement coating, said membrane having an adhesive coating thereon.

10. As an article of manufacture, a hydraulic cement shingle comprising a principal cementitious body and a paper membrane within having 20 thereon an emulsified coating.

11. As an article of manufacture, a weather 25 resistant element comprising a base, a layer of Portland cement on said base and a further layer comprising an oxychloride on said first layer and forming a smooth surfacing therefor.

12. As an article of manufacture, a building element comprising a fibre-containing base, a layer of adhesive on said base comprising a set 30 coating of a bituminous emulsion and a hardened coating of a plastic hydraulic cement bonded to said adhesive layer.

13. As an article of manufacture, a building 35 element comprising a paper membrane, a layer of adhesive on said membrane comprising a set coating of a bituminous emulsion and a hardened coating of a plastic hydraulic cement bonded to said adhesive layer.

NORMAN P. HARSHBERGER. 40
